COAL RANGE

Frank J. Freeland, Dowagiac, Mich., assignor to
 Round Oak Company, Dowagiac, Mich., a corporation of Michigan

Application January 27, 1936, Serial No. 61,075

6 Claims. (Cl. 126—211)

The present invention relates to improvements in coal ranges.

More specifically, the invention relates to an improved front hot plate construction and improved means for holding the hot plate in open position for refueling the range.

In coal ranges as heretofore constructed, the front hot plate which provides access to the fire box had suitably attached thereto a lever or lifting device for cooperation with a catch on the high shelf or closet for holding the hot plate in open position during the refueling operation. Such construction was disadvantageous in use, for the reason that when it was desired to raise the hot plate it was necessary to reach past the end of the range for manipulation of the lever or lifting device. Furthermore, when the lifting device was manipulated to raise the hot plate, still greater inconvenience was experienced in ascertaining the relation of the lifting device to the catch, it being necessary that the catch be placed in a notch in order to hold the hot plate in open position.

This construction, as heretofore employed in coal ranges, was particularly disadvantageous when, as is often the case, the fire box end of the range was located close to a wall or other object whereby access to the hot plate lifting and holding mechanism was very difficult.

A primary object of the present invention is the provision of an improved construction whereby the above-noted disadvantages are effectively overcome.

A further object of the invention is the provision of means for manually lifting the front hot plate of a coal range and means acting automatically to retain the hot plate in open position.

A further object of the invention is the provision of an improved front hot plate in a coal range which is capable of being manually lifted from the front of the range and spring actuated means acting automatically upon the hot plate being lifted to retain the same in open position.

A still further object of the invention is the provision in a coal range of a pivoted front hot plate which is constantly engaged by one end of a lifter bar, which bar is associated with a lifter lever and spring means in such manner that the lifter bar is yieldably urged against the hot plate with constantly increasing pressure as the hot plate is manually lifted for retaining the hot plate in open position.

A still further object of the invention is the provision in a coal range of a front hot plate which is associated with improved lifting and re-

taining means in such manner that the hot plate is free for ready disconnection with the range.

With the above objects in view, as well as others that will become apparent from the following disclosure, reference will be had to the accompanying drawing forming part of same, and wherein:

Fig. 1 is a rear view of a coal range in perspective, disclosing the application of the present invention, the high shelf or closet being removed for clarity of disclosure;

Fig. 2 is a similar view showing the front hot plate raised and being retained in raised position in accordance with the present invention;

Fig. 3 is a side elevational view of one of the elements of the mechanism for retaining the front hot plate in open position;

Fig. 4 is a perspective view of elements co-operating with the element shown in Fig. 3; and

Fig. 5 is a broken away view similar to Fig. 1, disclosing a modified embodiment of the invention.

Referring to the drawing by reference characters and wherein like characters designate like parts in the several views, R designates a range which may be of the usual construction, except for such modifications as are hereinafter described in connection with the present invention.

The range R embodies a fire box b which is normally closed by a front hot plate 10 suitably pivoted adjacent the center hot plate C for swinging movement from open to closed position and vice versa, the fire box b being in communication with the smoke flue F in accordance with coal range constructions now in use.

The front hot plate 10 is provided with means for effecting manual lifting thereof and which preferably comprises an extension 11, cast or otherwise, suitably secured to the front edge of the hot plate 10. The extension 11 normally rests in a recess 12 in the frame of the range and this extension, which is of angular formation, is provided with a suitable handle 13 of wire or other material which will be cool enough for comfortable handling. While this is the preferred means for manual lifting of the plate, it may be lifted with a lid lifter or other proper means.

Supported at the rear of the range is the improved means for maintaining the hot plate in open position. This means in its preferred form comprises a lever 14 pivotally connected with the range at 15 and which is, in turn, pivotally connected at 16 with the lower end of a lifting bar 17. The bar 17 extends generally in a vertical direction with the upper end thereof passing

through a suitable opening 18 into the fire box b and into loose engagement with the under side of the front hot plate 10.

The lever 14 is preferably of the form most clearly shown in Fig. 4 and which comprises a relatively wide angular head 19 provided with apertured ears 20. The head 19 is disposed over the oven door spring S, acting as a shield or cover therefor and between the body of the range 10 and a pivot support 21 suitably secured to the smoke flue F. The pivotal connection 15 comprises a long bolt 22, extending through the support 21 and the apertures in the ears 20.

The lever 14 is adapted to swing vertically in the operation of the device and the angular or L-shaped head 19 is so disposed relative to the spring S as to be free to move about the same and function as a shield in all positions thereof.

Secured to the range at 23 is one end of a coil spring 24, the opposite end of which is secured to the lifting bar 17 at 25.

In the closed position of the hot plate 10, as represented in Fig. 1 and at which time the lever 14 and lifting bar 17 are in their lowermost position, the coil spring 24 is substantially parallel with the lever 14 and with the axis of the spring or the line connecting the spring securing points 23 and 25 slightly above the pivotal connection 15 of the lever 14, whereby the upper end of the lifting bar 17 engages the under face of the plate 10 under a pressure insufficient to raise the plate. When the plate 10 is manually lifted, however, the bar 17 will move upwardly therewith, being always maintained in contact therewith through the spring 24. As the plate 10 is lifted, the upward pressure of the bar 17 will constantly increase, due to the increased leverage action of the spring 24, until the plate is in fully raised position, indicated in Fig. 2, and in which position it will be maintained by the bar 17. The bar 17 is preferably provided with a stop 26 for engagement with the frame of the range to limit upward movement of the bar 17.

In Fig. 5 is represented a modified construction, wherein foot-operated means are utilized in addition to the means already disclosed for manually lifting the hot plate 10. This means, which may be of various forms, preferably comprises a pedal 27, suitably pivoted at 28 beneath the range and connected with the pivot 16 by means of a link 29.

With this construction, the hot plate 10 may be raised upon foot actuation of the pedal 27 which, in turn, positively actuates the bar 17 and which, in turn, lifts the hot plate 10. This construction in no way interferes with the hand lifting of the plate and the pedal 27 including the link 29 is preferably balanced with respect to the pivotal connection 28 so as not to interfere with the action of the lever 14, bar 17, and spring 24.

It will be seen from the foregoing disclosure that the construction in accordance with the present invention materially reduces the effort and inconvenience heretofore experienced in refueling coal ranges, in that the front hot plate can be quickly and easily lifted from the front of the range and maintained in open position by automatic acting means.

The front hot plate 10 is preferably pivotally connected with the range by the well-known form of quickly releasable means which, in conjunction with the free engagement of the bar 17 with the plate 10, permits ready removal of the plate. The bar 17 may, however, be connected

with the plate 10 by suitable releasable means, if it should be so desired.

The weight of the ordinary type of hot plate is relatively small so that the gauge or strength of the spring 24 does not have to be very great. Due to this condition, when the fire has been refueled a slight downward pressure on the hot plate will return the same to closed position, where it will remain until again manually raised.

While I have disclosed a specific embodiment of the invention, the same is to be considered as illustrative, and not restrictive, the scope of the invention being defined in the subjoined claims.

What I claim as new and desire to secure by United States Letters Patent is:—

1. In a range construction, a pivotally mounted hot plate, means accessible from the front of the range for raising and lowering the hot plate, and spring actuated means acting automatically upon raising the hot plate to retain the same in raised position.

2. A range construction comprising a fire box and a pivotally mounted hot plate for normally closing the fire box, means accessible from the front of the range for manually raising and lowering the hot plate, and spring actuated means at the rear of the range automatically acting upon raising of the hot plate to retain same in raised or open position.

3. In a range construction, a pivotally mounted hot plate, a vertically movable member having one end thereof disposed beneath the hot plate and the other end thereof pivotally connected with the range, and spring means urging the vertically movable member upwardly, said pivotal connection and said spring means being so disposed that the vertically movable member moves upwardly upon manual lifting of the hot plate and exerts sufficient pressure on the hot plate to retain the same in open position when lifted to fully open position.

4. In combination with a coal range comprising a fire box and a pivotally mounted hot plate normally closing the fire box, means for manually lifting and closing the hot plate, a vertically movable bar having one end engaged with the hot plate, a lever having one end pivotally connected with the range and the other end pivotally connected with the other end of said bar, and a coil spring having one end connected with the range and the other end connected with said bar, the axis of said spring extending slightly above the pivotal connection of said lever with the range in the closed position of the hot plate for moving the bar upwardly with the lifting movement of the hot plate and the said axis extending substantially above said pivotal connection in the open position of the hot plate for urging said bar upwardly under sufficient pressure to maintain the hot plate in open position.

5. The construction defined in claim 4 wherein said lever includes a head adjacent the pivotal connection thereof with the range for providing a shield for an oven door spring.

6. In a range construction, a pivotally mounted hot plate, means for raising and lowering the hot plate, a vertically movable lifting bar, and a spring connected with the lifting bar for constantly urging same into engagement with the hot plate for maintaining the hot plate in raised position.

FRANK J. FREELAND.
